(57) **CLAIM**

The ornamental design for an electric range, as shown and described.

DESCRIPTION

FIG. 1 is a front perspective view of an electric range, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the portion 8 delineated in FIG. 1.

The dot-dot-dash broken lines encircling enlarged portions of the claimed design form no part of the claimed design. The remaining broken lines in the figures depict portions of the electric range that form no part of the claimed design.
